UNITED STATES PATENT OFFICE.

GEORGE HARDY, OF PONT ROUGE, QUEBEC, CANADA, ASSIGNOR TO THE MILLS WORKS
& MACHINERY LIMITED, OF PONT ROUGE, QUEBEC, CANADA.

PASTE REGULATOR FOR PAPER-MAKING MACHINES.

1,406,009.

Specification of Letters Patent. Patented Feb. 7, 1922.

Application filed June 26, 1920. Serial No. 391,897.

To all whom it may concern:

Be it known that I, GEORGE HARDY, a subject of the King of Great Britain, residing at Pont Rouge, Province of Quebec, Canada, have invented certain new and useful Improvements in Paste Regulators for Paper-Making Machines; and I do hereby declare that the following is a full, clear, and exact description of the invention, such as will 10 enable others skilled in the art to which it appertains to make and use the same.

The present invention relates to apparatuses for regulating the flow of paste to paper making machines and is a continuation 15 of my former Patent No. 1,322,016, dated November 18, 1919.

The purpose of the present invention is to generally improve such regulators whereby the flow of paste will be under better control so that paste of various consistencies 20 may be delivered in the proper amounts to the paper making machine.

A further object of the invention is to provide an automatic controlled apparatus 25 for regulating the flow of paste to the paper making machine so that sheets of paper of uniform thickness will be continuously made throughout the manufacture thereof and one which may be adjusted so that sheets of 30 paper of various thickness may be produced.

With the above and other objects in view which will hereinafter appear as the description continues, the invention consists of the novel features of construction, combination and formation of parts as will be 35 hereinafter more fully described and particularly pointed out in the appended claims.

In the accompanying drawings:

Figure 1 is a vertical section through a 40 portion of a paste reservoir having the improved regulator applied thereto showing one embodiment of the invention; and

Figure 2 is a similar view, illustrating a slightly modified form of the invention.

Referring now more particularly to the 45 accompanying drawings wherein like and corresponding parts are designated by similar reference characters throughout the several views.

The numeral 1 indicates a paste reservoir 50 or tank in which the paste is stored or mixed before being formed into paper. This reservoir is provided with the usual outlet spout 2 having connected thereto the upper end of 55 an outlet pipe or elbow 3. Secured as at 4

to the outer end of the elbow is a vertical basin 5 having its upper end terminating below the paste line within the reservoir. Surrounding this basin 5 is a trough 6 having an outlet or spout 7 from which the paste 60 travels to the paper making machine. The lower portion of the elbow 3 is provided with a drain opening closed by a plug 8 whereby any paste trapped within the elbow 65 may be removed or water drained therefrom when cleaning the same. From this paste conveying means it will be understood that the paste may flow from the reservoir 1 to the paper making machine.

The present invention resides in means for 70 keeping the paste under automatic control while being so conveyed. Arranged within the spout 2 is gate valve 9 comprising an angular plate pivotally supported on a horizontal shaft 10 journaled within suitable 75 bearings carried by the reservoir 1. Pivotally connected to this shaft 10 is an arm or bar 11 having an internally threaded sleeve 12 through which extends an adjustable bolt 13 and the lower end of this bolt 80 is connected to the gate 9. The flow of the paste from the reservoir normally tends to open this gate and the opened position of the gate is limited by the bolt 13. The outer end of the bar 11 is provided with an enlarged slotted end 14 in which is adjustably supported the upper end of the link 15. The lower end of this link 15 is adjustably secured within the slotted end 16 of a lever 17. Set screws 18 are arranged within the slotted 90 ends 14 and 16 of the bar and lever respectively, so that the link 15 may be retained in its adjusted position. A bracket 19 is supported upon the elbow 3 and pivotally connected thereto as at 20 and carried by 95 this bracket and extending therethrough is a rod 22 having its upper end connected through the slot and pin connection 23 to the lever 17 and a float 24 is carried by the lower end of this rod 22. This float extends 100 within the basin 5 and rises or lowers within the paste according to the latter's specific gravity and the vertical movement of this float controls the opening and closing of the gate 9.

In the slightly modified form of the invention as illustrated in Figure 2 the gate 25 is pivotally supported, as at 26 and pivotally connected to the gate is a bolt 27 105 adjustably supported within a sleeve 28 car-

ried by one end of an automatic lever 29. This lever 29 is pivotally supported as at 30 upon the elbow 3 and has formed therewith a crank arm 31. A Y-shaped lever 32 is pivotally connected as at 33 to the bracket 19 and one arm thereof is slotted as at 34 in which is adjustably connected one end of a rod 35 and the opposite end of this rod is pivotally connected to the arm 31. This 10 lever 32 is provided with a counter weight 36 and its arm 37 is connected to the vertical rod 22 by means of the slot and pin connection 38.

From either of the regulators herein shown, it will be understood that when a light mixture of paste flows from the reservoir to the basin the float will descend whereby the gate valves will be opened freely, but if a heavy mixture of paste is provided in the 20 reservoir the float will rise thereby closing the valves limiting the flow of the paste and in this manner the required amount of paste flowing to the paper making machine will be under automatic control so that sheets of 25 paper of the same thickness will be made throughout its manufacture.

The desired thickness of the sheets of paper can be obtained by adjusting the rod 35 or the link 15.

30 The operator, when knowing the consistency of the paste within the reservoir may adjust the gates through the bolts 13 or 27 so that the required amount of paste will flow from the reservoir.

35 Having thus fully described my invention, what I claim as new and desire to secure by Letters Patent is:—

1. A paste regulator for paper making machines comprising a reservoir, an outlet 40 leading therefrom, a basin attached to said outlet, a gate arranged within the outlet and consisting of angularly disposed integral sections, a float disposed above the upper end of the basin and extending therein, an arm actuated by the float, a rod pivoted to the gate and adjustably connected to the arm for adjustably supporting the gate, and means operatively connecting the arm with the float.

45 2. In a paste regulator of the character

described, the combination of a pivotally supported gate including angularly disposed integral sections, a float, an arm having operative connection with said float and with the gate whereby the latter may be opened and closed upon movement of the float, a rod attached to the float, a lever to which the rod is attached, a link movably connected to the arm and the lever for controlling the swinging movement of the gate, and screw elements carried by the arm and lever for adjusting the ends of the link relative thereto.

3. The combination with a paste reservoir having an outlet, a gate including two angular integral sections arranged within said outlet, a float, an arm adjustably connected to said gate, a threaded rod attached to the gate and passing through the arm for adjustably connecting the gate and the arm, and means for connecting said arm to the float.

4. A paste regulator for paper making machines comprising a reservoir, an outlet pipe leading from the said reservoir, a basin carried by the outlet pipe, a pivotally supported gate disposed within the outlet pipe, 75 said gate including angularly disposed integral sections, a pivotally supported arm, a rod passing through said arm and pivotally connected to the gate for adjustably connecting the gate to the arm, a bracket supported by the outlet pipe, a lever pivotally connected to said bracket, said lever and arm having longitudinally disposed slots formed therein, a link adjustably connecting said lever and arm and slidably in said 80 slots, screw elements passing through the slots and ends of the link for adjusting the latter, a float arranged within said reservoir, and a rod connecting the float with the lever; substantially as and for the purposes set 85 forth.

In witness whereof I have hereunto set my hand.

GEORGE HARDY.
